(57) CLAIM

The ornamental design for a clothes ruffle, as shown and described.

DESCRIPTION

FIG. 1 is a front view of a clothes ruffle shown on a first article of clothing, such as a coverall; and, FIG. 2 is a front view of the clothes ruffle shown on a second article of clothing, such as a footie.

The broken lines of FIG. 1 and FIG. 2 are for illustrative purposes only and form no part of the claimed design.

1 Claim, 2 Drawing Sheets
